US00D944781S

(12) **United States Design Patent** (10) **Patent No.:** **US D944,781 S**
(45) **Date of Patent:** **** Mar. 1, 2022**

(54) **ANTENNA**

(71) Applicant: **MAKE GREAT SALES LIMITED**,
Wan Chai (HK)

(72) Inventors: **Bruce Peter Cran**, Ho Chi Minh (VN);
Kin Choi Lee, Wan Chai (HK)

(73) Assignee: **Make Great Sales Limited**, Hong
Kong (HK)

(**) Term: **15 Years**

(21) Appl. No.: **29/707,311**

(22) Filed: **Sep. 27, 2019**

(51) **LOC (13) Cl.** **14-03**

(52) **U.S. Cl.**

USPC **D14/230**

CLAIM

The ornamental design for an antenna, as shown and described.

DESCRIPTION

FIG. 1 is a rear isometric view of a first embodiment of an antenna, in accordance with our design;

FIG. 2 is a front isometric view of the antenna of FIG. 1; FIG. 3 is another rear isometric view of the antenna of FIG. 1;

FIG. 4 is a rear view of the antenna of FIG. 1;

FIG. 5 is a front view of the antenna of FIG. 1;

FIG. 6 is a right-side view of the antenna of FIG. 1;

FIG. 7 is a left-side view of the antenna of FIG. 1;

FIG. 8 is a top view of the antenna of FIG. 1; and

FIG. 9 is a bottom view of the antenna of FIG. 1.

FIG. 10 is a rear isometric view of a second embodiment of an antenna, in accordance with our design;

FIG. 11 is a front isometric view of the antenna of FIG. 10;

FIG. 12 is another rear isometric view of the antenna of FIG. 10;

FIG. 13 is a rear view of the antenna of FIG. 10;

FIG. 14 is a front view of the antenna of FIG. 10;

FIG. 15 is a right-side view of the antenna of FIG. 10;

FIG. 16 is a left-side view of the antenna of FIG. 10;

FIG. 17 is a top view of the antenna of FIG. 10; and,

FIG. 18 is a bottom view of the antenna of FIG. 10.

1 Claim, 8 Drawing Sheets
